UNITED STATES PATENT OFFICE.

CHARLES T. WESTLAKE, OF ST. LOUIS, MISSOURI, ASSIGNOR TO TRANSOM DRAFT GEAR COMPANY, OF ST. LOUIS, MISSOURI, A CORPORATION OF DELAWARE.

DRAFT-GEAR FOR RAILROAD-CARS.

No. 839,350.

Specification of Letters Patent.

Patented Dec. 25, 1906.

Application filed October 15, 1906. Serial No. 339,031.

To all whom it may concern:

Be it known that I, CHARLES T. WESTLAKE, a citizen of the United States, residing at St. Louis, in the State of Missouri, have 5 invented a new and useful Improvement in Draft-Gear for Railroad-Cars, of which the following is a specification.

My invention relates to draft-gear for a railroad-car, and particularly to that class of 10 draft-gear in which the springs are arranged either singly with follower-plates or one behind the other with or without follower-plates tandemwise and in alinement with the longitudinal center of the car and applied 15 to a metallic block or housing or directly to the body-bolster located between narrowly-spaced draft members or middle longitudinal sills of the car, which, owing to the limited space between the sills, prevents the use 20 of a self-centering draft-gear having the springs on each side of the longitudinal center of the car, such as that described in the United States Letters Patent granted to Harry M. Pfleger and dated, respectively, 25 October 18, 1904, No. 772,370; January 10, 1905, No. 779,559, and January 27, 1906, No. 813,427; and my invention has for its object to render the said single or tandem spring draft-gear under these conditions self-centering.

My invention consists in features of novelty, as hereinafter described and claimed, reference being had to the accompanying drawings, forming part of this specification, 35 whereon—

Figure 1 is a horizontal section on line 1 1 in Fig. 2 through my improved draft-gear having the springs arranged tandemwise without follower-plates and applied to a metallic block fixed between the narrowly-spaced middle longitudinal metal sills or draft members of a railroad-car; Fig. 2, a vertical longitudinal section through the same on line 2 2 in Fig. 1; Figs. 3 and 4, vertical transverse sections thereof on lines 3 3 and 4 4, respectively, in Fig. 2; and Fig. 5, a reduced scale view of the draft-gear corresponding to Fig. 3 as applied to a car-body bolster in lieu of the separately-constructed 45 block shown in Figs. 1 to 4.

Like letters and numerals of reference denote like parts in all the figures.

a represents the narrowly-spaced middle

longitudinal metal sills (or draft members) of a railroad-car, between which is arranged a 55 block or housing *b*, having in the present case two opposite members *1*, adapted to bear against the inner upright faces of the sills *a*, to which they are fixed by rivets or bolts *2* and united together integrally by an upright web *3*, which when the block *b* is used in lieu of a body-bolster in combination with the truck-bolster is perforated centrally and otherwise suitably shaped thereat for the passage therethrough of the king-bolt, (not shown,) the body center plate *4* in this case bearing against the under side of the block *b* and fixed to the sills *a* by rivets *4'* or bolts, as shown.

In or projecting from the front and rear 70 sides of the web *3* are formed two recesses or pockets *5* *5'*, respectively, which are alined to the longitudinal center of the car, the front pocket *5* being adapted to receive the inner end portion of the buffering-spring *6* of 75 the draft-gear and the rear pocket *5'* to receive the inner end portion of the draft-spring *6'*.

c is the draw-bar, having at its inner end a pocket *7*, which is similar and opposite to 80 the pocket *5* and adapted to receive the outer end portion of the buffering-spring *6*.

d is a yoke having on its inner face a pocket *8*, similar and opposite to the pocket *5'* and adapted to receive the rear end portion of the draft-spring *6'*, the arms *9* of the yoke *d* passing through openings *10* therefor through the web *3* of the block *b* and coupled, respectively, at their free ends to the draw-bar *c* (preferably at each side thereof) by a 90 pin or bolt *e*, which is preferably fixed in the draw-bar *c* and passes freely through a slot *11*, formed thereat longitudinally and vertically through the arm *9*, the pins *e* being adapted to engage the front end of the slot *11* during the pulling movement of the draw-bar *c* when in its normal position or in central alinement to the longitudinal center of the springs *6* *6'* and car. On a lateral movement of the draw-bar *c* to either side of the 95 said center when passing round curves or otherwise the pin *e* on that side from which the draw-bar is constrained by the couplers will remain normal or in engagement with the front end of its corresponding slot *11*, while the opposite pin *e* will travel in its slot *11* ra-

dially to the said engaged pin *e*, the yoke *d* meanwhile remaining normal or unaffected, whereby the pocket *7* in the draw-bar *c* will compress the spring *6* toward that side adjacent to the moving pin *e*, so that on the release of the draw-bar *c* the latter will be returned by the reaction of the spring *6* to its normal position, or, in other words, self-centered, or, if desired, the pins *e* in lieu of being fixed in the draw-bar *c* and the slots *11* formed through the arms *9*, as above described, the arrangement may be reversed—that is to say, the pins *e* fixed in the arms *9* and the slots *11* formed through the draw-bar *c*, the operation in both cases being the same. The same arrangement and operation of the draw-bar *c* and yoke *d* coupled thereto, applies also to a draft-gear having a single spring passing through an opening in

20 a block, or body-bolster combined with fol-

25 lower plates, and alined to the longitudinal center of the car.

What I claim as my invention, and desire to secure by Letters Patent, is—

25 1. In draft-gear of the character described, the combination of the draw-bar adapted to engage one end of a spring, a yoke adapted to engage the other end of the spring and having a slot through each arm thereof longitudinally thereto, a housing for the spring having a passage therethrough for the said arms, and two opposite pins fixed to the draw-bar and passing freely through the said slots, the said pins being adapted to en-

30 gage the outer ends of the said slots during the pulling movement of the draw-bar when alined to the longitudinal center of the

35 spring, and to be moved radially to each

other in the said slots about the said ends respectively when the draw-bar is inclined laterally to the said center, substantially as described and for the purpose set forth.

2. In draft-gear of the character described, the combination with the springs, of the draw-bar adapted to engage the front end of the "buffing-spring," a yoke adapted to engage the rear end of the "draft-spring" and having a slot through each arm thereof longitudinally thereto, a housing for the springs having a passage therethrough for the said arms, and two opposite pins fixed to the draw-bar and passing freely through the said slots, the said pins being adapted to engage the outer ends of the said slots, during the pulling movement of the draw-bar when alined to the longitudinal center of the springs, and to be moved radially to each other in the said slots about the said ends, respectively, when the draw-bar is inclined laterally to the said center, substantially as described.

3. In draft-gear of the character described, the combination with two members, the draw-bar and the yoke, of two opposite pins fixed in one of the said members and adapted to engage in slots formed through the other said member longitudinally thereto, substantially as described and for the purpose set forth.

In testimony whereof I have signed my name to this specification in the presence of two subscribing witnesses.

CHARLES T. WESTLAKE.
